UNITED STATES PATENT OFFICE.

WILLIAM W. McMILLEN AND FLOYD ANDERSON, OF McCOOK, NEBRASKA.

HAME STAPLE AND CLIP CONNECTOR.

No. 836,525.

Specification of Letters Patent.

Patented Nov. 20, 1906.

Application filed December 21, 1905. Serial No. 292,796.

To all whom it may concern:

Be it known that we, WILLIAM W. McMILLEN and FLOYD ANDERSON, citizens of the United States, residing at McCook, in the county of Redwillow and State of Nebraska, have invented certain new and useful Improvements in Hame Staple and Clip Connectors; and we do hereby declare the following to be a full, clear, and exact description of the invention, such as will enable others skilled in the art to which it appertains to make and use the same.

Our invention relates to hame staple and clip connectors.

It has for its object to reduce wear on the clip and staple as well as upon the hame.

The invention consists in the features of construction and combinations of parts hereinafter described, and more particularly 20 pointed out in the claims concluding this specification.

In the accompanying drawings, illustrating the preferred embodiment of our invention, Figure 1 is an elevation of a portion of a hame and the front end of a trace provided 25 with our improved connecting device. Fig. 2 is a transverse sectional view taken on the line $x-x$ of Fig. 1.

While the preferred embodiment of our invention is illustrated in the accompanying drawings and its construction and operation are described in this specification, the right is reserved to make such changes from the construction shown and described herein as the 35 scope of the claims hereto appended will permit.

Referring more particularly to the drawings, 1 is the hame, to which is secured the staple 2, carrying a bracket-plate 3, suitably 40 perforated at 4 to support a ring, (not shown,) whereby the pole-strap of the vehicle may be connected to the hame. The clip, which is secured to the end of the trace 5, comprises oppositely-extending arms 6 and a cross-piece 7. The wear part or piece 8, which is 45 interposed between the staple and bolt of the clip, is preferably made of iron and has two grooves 9 and 10 running transversely to each other and adapted to engage said staple and pin, respectively. The outer surface of 50 said wear-piece is formed to fit neatly between the arms of the clip and staple, whereby easy movement of the parts is permitted without

unnecessary noise or lost motion. The arms 6 and cross-piece 7 of the clip are preferably 55 made integral, as shown. Said wear parts have surface enough to wear on so that it is impossible for them to wear out and they will last the lifetime of a harness, consequently not necessitating the replacing of the 60 clips or staples. It will be noted that the grooves are so deep that all contact between the clip and staple is prevented. It will be noted that the wear-piece 8 turns freely on the staple horizontally as lateral pressure is 65 exerted thereon by the staple and that the clip turns freely on the said wear-piece as the line of draft changes vertically, whereby the wear-piece moves freely with the clip and the clip moves freely in the wear-piece, also that 70 the wear-piece is so constructed and combined with the clip and staple that it is adapted to move horizontally between the portions of the staple which project from the hame. The wear-piece has two pivot-bearings, one in its outer groove between the staple and the wear-piece and the other in its inner groove between the wear-piece and the clip. 75

Having thus described our invention, what 80 we claim as new, and desire to secure by Letters Patent, is—

1. The combination, with a hame staple and clip, of a wear-piece loosely interposed between them and having grooves, arranged 85 transversely to each other, for engaging said staple and clip.

2. The combination, with a hame staple and clip, of a wear-piece loosely interposed 90 between them and having grooves, arranged transversely to each other, for engaging said staple and clip, said grooves being of sufficient depth to prevent contact between said staple and clip.

3. The combination, with a hame staple 95 and a clip comprising oppositely-extending arms and a cross-piece, of a wear-piece loosely interposed between said staple and clip, and having grooves, arranged transversely to each other, for engaging said staple and cross-piece.

4. The combination, with a hame staple and a clip comprising oppositely-extending arms and a cross-piece, of a wear-piece loosely 105 interposed between said staple and clip, and having grooves, arranged transversely to

each other, for engaging said staple and cross-piece, said grooves being of sufficient depth to prevent contact between said staple and clip.

5 5. The combination, with a hame staple and clip, of a wear-piece interposed therebetween and having pivot-bearings on opposite sides thereof for the hame staple and clip.

In testimony whereof we affix our signatures in presence of two witnesses.

to

WILLIAM W. McMILLEN.
FLOYD ANDERSON.
